ELECTRIC DISCHARGE TUBE

Huibert Gerard Boumeester, Eindhoven, Netherlands, assignor to N. V. Philips' Gloeilampenfabrieken, Eindhoven, Netherlands

Application October 4, 1935, Serial No. 43,505
In Germany October 4, 1934

2 Claims. (Cl. 250—27.5)

The invention relates to electric discharge tubes and more particularly to discharge tubes of high power which serve, for example, for the generation or amplification of electrical oscillations.

5 Between the electrodes of power tubes very high voltages may be set up, and the supporting and current supply members of the electrodes must be mounted at a comparatively great distance from one another. Particular attention 10 must be given to the mounting of the grid relatively to the other electrodes and to the supporting and supply members.

It has been suggested to introduce the cathode lead thru the envelope of the discharge tube in 15 the usual manner by means of a stem and press and to attach the grid to a ring enclosing the stem. This manner of attachment entails the disadvantages of short distances between the supporting and supply members of the grid and 20 the cathode members, resulting in spark-over or electrolysis or dielectric losses which destroy the interjacent insulating material. With these forms of construction there may be produced, even without the material being attacked, leakage currents which injuriously affect the 25 operation of the tube.

The above mentioned drawbacks may be partly overcome by providing the stem with an outer concentric extension as shown, for example, in 30 United States Patent 1,718,906, issued June 13, 1929 to Mouromtseff. However, in this construction there arise other drawbacks in that such tubes with very high cathode currents, the cathode supply leads must have very large dimensions and must, therefore, be sealed into a wide bulb. In the last mentioned form of construction in which the stem tube is provided with extensions, the cathode stem has to be first sealed 35 into a cylindrical body and then must this body be secured to the bulb. It is consequently necessary to employ in this case a wider bulb than is required for the form of construction where the grid is clamped directly to the cathode stem. It may be mentioned that with a bulb diameter of 40 45 16 cms. there exists an atmospheric pressure of about 200 kgs. which, pressing the sealing-in zone, may crack the glass.

A further drawback of the above described form of construction is that it is not easy to 50 heat, during exhaust, the wires or strips which connect the grid to the leading-out member to the temperature required for creating a satisfactory vacuum.

A tube constructed in accordance with this 55 invention overcomes the mentioned disadvan-

tages in a simple manner. According to this invention the supporting and current supply members of the grid of an electric discharge tube of high power are housed in two or more lateral projections of the tube. It is advantageous to 5 construct the discharge tube according to the invention in such manner that it has two lateral tubular projections consisting of glass, quartz or similar material and is closed by means of a metallic body as, for example, ferro-chromium to which are secured the supporting and current supply members of the grid.

Tubes constructed according to the invention provide between the grid and the other electrodes a long insulated path without increasing the diameter of the bulb. Further, it is easy to deprive the grid supply members within the tube of occluded gases simply by connecting them to a source of voltage.

Further, the construction according to this invention is much more solid than with the use of a clamping strip surrounding the stem tube or of extensions provided on the stem tube. At the other end, the grid may be supported by the anode with the aid of insulating material such as 25 quartz.

If a tube according to the invention is employed for short wave purposes, in which event large grid currents are produced, the leading-out members may be connected in parallel. In 30 one embodiment of the invention this parallel connection may be made by connecting the ferro-chromium bodies to one another by means of a strip or a tube of metal, for example, an aluminum tube, and by providing said strip or tube 35 with a current supply member. This form of construction, further, may increase the dissipation of heat from the glass-metal joint. The cooling of this joint may be improved by making the grid supporting and supply members 40 which are secured to the ferro-chromium bodies of metallic tubes instead of solid metal. Cooling may be effected by two small tubes which empty 45 into a hollow extension provided at the end of the obturating body and thru which cooling water is caused to circulate.

The invention will be explained more fully with reference to the accompanying drawing in which—

Figure 1 represents, by way of example, a tube 50 constructed according to the invention, and

Figures 2 and 3 show details of said tube.

In Figure 1, numeral 1 denotes the anode of a discharge tube, which anode forms at the same time part of the envelope wall. This portion of 55

the tube may be artificially cooled in any known manner. To one of the ends of said electrode is sealed a member 2 which consists of glass, quartz or similar material and within which the various support and current supply members of the electrodes are located. Said member 2 has a stem or foot 3 furnished with two members 4 and 5 consisting of ferro-chromium and having attached to it current supply wires 6 and 7 of the 10 cathode.

The tube portion 2 has two lateral tubular projections 8 and 9 provided at their ends with metal bodies 10 and 11 of, for example, ferro-chromium to which are secured the current supply and supporting members 12 and 13 of the grid, which members may be hollow copper rods. These rods are connected by means of strips 14 and 15 to the side rods of the grid 16.

As is shown in detail in Figure 2 the points at 20 which the ferro-chromium bodies are sealed to the outer wall may be artificially cooled. For this purpose two small tubes 17 and 18 are led into the interior of the hollow bodies 10 and 11, which cool the sealing joint quite satisfactorily.

25 Figure 3 shows the manner in which, more particularly if the tube is employed for short wave purposes, the ferro-chromium bodies 10 and 11 may be connected to one another. The connection is established with the aid of a hollow ring 30 22 of aluminum which is flattened at both ends 23 and 24 and which is provided at its center with a current supply member 25.

It appears from the form of construction shown 35 in Figure 1, that between the current supply members of the electrodes there are provided leakage paths of maximum length without increasing the diameter of the bulb. This becomes obvious when the form of construction represented in Figure 1 is compared to the form of construction shown in Mouromtseff, *supra*.

It may be observed that although Figure 1 represents one embodiment of the present invention, various modifications are possible. Thus, for example, it is not absolutely necessary that the projecting tubular parts should extend exactly laterally from the discharge tube; it would be possible, for example, to provide them at the top and in line with the discharge tube.

I claim:

1. A high power electron discharge device comprising an envelope with a cylindrical anode sealed gas tight to an axially extending glass section, cathode leads extending thru and sealed in the glass section opposite the anode seal, a grid in and symmetrically spaced from the anode, the sole support and lead-in means for said grid comprising a plurality of metallic bodies sealed at circumferentially spaced points in the wall of said glass section intermediate the cathode and anode seals, and rigid supporting members, each member being mechanically secured at one end to one of said bodies and at the other end to said grid.

2. An electric discharge tube of the high power type comprising an envelope with a cylindrical anode, an axially extending glass cylinder sealed gas tight to said anode with lateral projections intermediate the anode-to-glass seal and the outer end of the glass cylinder, said anode containing a cathode and a grid, a plurality of supporting and current supply members for the grid housed in said glass cylinder, the lateral projections being sealed gas tight at their ends with inwardly extending metallic bodies to the inner ends of which the current supply and supporting members of the grid are secured, said bodies being short-circuited exteriorly of the envelope by a short conductor.
